UNITED STATES PATENT OFFICE.

DANIEL G. BOLTON, OF CAMDEN, NEW JERSEY.

ELECTRICAL INSULATOR.

No. 880,121.

Specification of Letters Patent.

Patented Feb. 25, 1908.

Application filed November 23, 1906. Serial No. 344,752.

To all whom it may concern:

Be it known that I, DANIEL G. BOLTON, a citizen of the United States, residing at Camden, in the county of Camden and State 5 of New Jersey, have invented certain new and useful Improvements in Electrical Insulators, of which the following is a specification.

My invention relates to improvements in 10 electrical insulators in which low tension wires may be securely fastened.

A further object of my invention is to protect or insulate all parts of the wire, including the material it is fastened to.

15 A further purpose of my improved insulator is its adaptability to different grades of material to which it may be attached, permitting installations to be accomplished much more rapidly.

20 In carrying out the invention in an approved form, whereby one or more wires may be readily attached to the desired house casings or material, disks of insulated material are held in proximity on a driving pin or 25 screw. Between said disks is a flexible bushing of insulated material, and by the placement of wires between the disks and the insulator forced into its attachment, the wires will be securely fastened.

30 The invention is illustrated in the accompanying drawings, in which—

Figure 1 is a side elevation illustrating the invention; Fig. 2 is a plan view of Fig. 1; Fig. 3 is a perspective view of the invention; Fig. 35 4 a cross-section view of Fig. 3 on the line 4—4; Fig. 5 is a side elevation, illustrating a double insulator; Fig. 6 is a plan view of Fig. 5; Fig. 7 is a cross-section view of Fig. 5 on the line 7—7.

40 Referring to the drawings in which similar letters denote corresponding parts, "A" designates the material for attachment, "B" the wire and "C" the insulator for attaching.

"D" as shown in Figs. 5, 6 and 7, represents a double insulator.

45 Details of my invention are shown in Figs. 3 and 4. Insulator C consists of a butt end pin or screw as C², a disk or plate of insulated material C³ secured to C² by means of its ori-

50 fice C⁴, C² being insulated by a flexible bushing as C⁵. C⁶ is a similar disk as C³ and secured to C² in like manner. Pin C² is preferably provided with a pointed end as C⁶, to permit it to be more rapidly driven or attached.

55 Wires as B and B¹ are placed between disks C³ and C⁶ and by forcing pin C² in material

as A being of wood or soft brick nature, disks C³ and C⁶ are forced together. The soft rubber tube bushing as C⁵ permits this to be accomplished. B and B¹ are thereby securely fastened to A, as shown in Figs. 1 and 2, by insulators C and C¹.

It will be noticed the wires here illustrated are of the twisted pair variety, and that by tightening these pairs it has a tendency to 60 draw the wires close to the pin D² as shown in Fig. 7. The invention is not limited to the twisted pair or two or more conductor circuits. A single wire can be run and secured to the insulator by the tie wire method, 70 and then kept perfectly taut by the method described. I also do not wish to limit the invention as to the method of fastening as pin C². A screw, although not as rapid, in some cases might be desirable.

75 In Figs. 5, 6 and 7 are shown the double insulators D and D¹ securing two pair of wires as B³ and B⁴, and B⁵ and B⁶, to the material as T¹. In Fig. 7 will be seen wires B³ and B⁴ secured between insulated disks 80 D³ and D⁵ and insulated from pin D² by D⁴; wires B⁵ and B⁶ secured between insulated disks D⁵ and D⁸ and insulated from pin D² by insulated bushing D⁷, and also insulated from A¹ by disk D⁸. Said pin D² 85 being permitted to be forced into A¹ by its pointed end D⁶. The members of the insulator retain their relations by its butt end or head D⁹.

What I claim and desire to secure by 90 Letters Patent is—

1. An electric insulator, comprising a pin, disks thereon spaced apart, and a sleeve or bushing of flexible insulating material around the pin between the disks.

95 2. An electric insulator, comprising a pin having a head on one end and constructed at its opposite end for attachment to its support, a series of disks on said pin, and sleeves or bushings of flexible insulating material 100 around the pins and spacing the disks apart.

3. An electric insulator, comprising a headed pin, wire clamping disks loose on the pin, and a flexible elastic sleeve or bushing around the pin between the disks.

105 In testimony whereof I affix my signature in presence of two witnesses.

DANIEL G. BOLTON.
